UNITED STATES PATENT OFFICE.

HORATIO S. KEMP, OF MILWAUKEE, WISCONSIN.

BOX-LOOP FORMING AND EMBOSSED MACHINE.

No. 830,077.

Specification of Letters Patent.

Patented Sept. 4, 1906.

Application filed September 1, 1905. Serial No. 276,688.

To all whom it may concern:

Be it known that I, HORATIO S. KEMP, residing in Milwaukee, in the county of Milwaukee and State of Wisconsin, have invented new and useful Improvements in Box-Loop Forming and Embossing Machines, of which the following is a description, reference being had to the accompanying drawings, which are a part of this specification.

10 My invention is of improvements in box-loop forming and embossing machines whereby automatic movement is secured, a more rapid operation is accomplished, and a better and more satisfactory result is obtained than 15 has heretofore been had in the manufacture of box-loops, especially loops of the general form and character of those desirable and heretofore made crudely on the straps and members of harness and other articles made 20 of leather.

The invention consists of the mechanism, its parts and combinations of parts, as herein described and claimed, or the equivalents thereof.

25 In the drawings, Figure 1 is a side elevation of my improved forming and embossing machine. Fig. 2 is a vertical section on line 2 2 of Fig. 1. Fig. 3 is a section on line 3 3 of Fig. 1 looking downwardly. Fig. 4 represents the incised and thereby ornamented 30 surface of the plate, adapted for embossing and thereby finishing the outer surface of the box-loop. Fig. 5 is a perspective of a box-loop on a harness-strap formed in my machine. Fig. 6 is an end elevation of a modified form of the invention, and Fig. 7 is a section on line 7 7 of Fig. 6, looking upwardly, 35 of the modified form of machine shown in Fig. 6.

40 My improved machine is preferably formed throughout of metal and advisably chiefly of steel, though some of the parts—such, for instance, as the embossing - plate—may be made of brass.

45 In the drawings, A represents the base, advisably in the general form of a block adapted to rest on a support, the base being cut away across it medially in the top, forming a floor 2, with side walls 3 3, advisably flaring a 50 little outwardly upwardly from the floor to the top of the base. Within the socket or recess in the base thus formed there are angled levers or jaws 4 4, the upright arms of which levers are pivoted medially to the end 55 upwardly-projecting portions or standards 5 of the base conveniently by means of short

straps 6 6, secured to the respective sides of the standards in pairs advisably by means of pins 7, fixed in the straps and entering sockets therefor in the standards, and by screws 8, 60 passing through the straps and turning into the standards, which straps are provided with inwardly-projecting stud pivot-pins 9 that enter the jaws 4 4, permitting the jaws to tilt thereon. The jaws are so formed that 65 the lower laterally-projecting arms thereof may abut against each other when the upwardly-projecting arms are open, in the manner shown in Fig. 1. A vertically-disposed supporting-pin 10, mounted in a socket 70 therefor in the base A directly underneath the ends of the laterally-projecting lower arms of the jaws, is held upwardly yieldingly by a spring 11, this spring-actuated pin being disposed and adapted to throw the upper 75 arms of the jaws apart or open, as shown in Fig. 1. The jaws 4 are so formed that when they close toward each other and against the box-loop their bottom surfaces will come to rest on the floor 2 and their lateral edges below their pivots may also come to rest against the walls 3, or, in other words, the jaws 4 80 when in operation seat themselves on the floor 2 and may bear against the walls 3 on surfaces thereof below the pivots 9. 85

The jaws 4 are provided with face-pieces 12 12, opposite and complementary to each other on the inner surfaces of the jaws, adapted for forming and finishing the sides of a box-loop, which face-pieces are secured in 90 position by any suitable means, which may be pins or rivets 13, extending from the face-pieces into or through the jaws in such manner that the face-pieces may be removed readily for replacement by other face-pieces 95 when the old ones have become worn or it is otherwise desirable to change them. In setting the face-pieces 12 in the jaws sheet-metal backings 14 may be interposed, if found desirable. These face-pieces may have such 100 finishing on their exposed and opposite surfaces as desired, the face-pieces in the drawings being grooved vertically for giving a ribbed effect to the sides of the box-loop when formed in this machine. At the lower 105 ends of these face-pieces and between them within the jaws and for forming the bottom of the box-loop there is a loop-plate 15, loosely resting on the upper surfaces of the laterally-projecting arms of the jaws, which 110 loop-plate is advisably provided with downwardly-extending retaining-pins 16, which

enter sockets therefor in the ends of the laterally-extending arms of the jaws, by which means the loop-plate is held against accidental displacement. The upper and forming surface of this plate 15 may be of any form desired, but is preferably concave in transverse section, as shown in the drawings.

- For forming and finishing by embossing or otherwise the outer surface of the box-loop 10 an embossing or finishing plate 17 is required, which plate must be located in the machine substantially opposite the lower loop-plate 15, and this plate is fixed to and thereby supported in position on and movably with an 15 overhanging plate-arm 18, provided with rigidly-dependant legs 19, which slide or telescope in sockets therefor in the base A and therein in the standards 5. The plate-arm is supported at a distance above the loop-plate 20 15 yieldingly by a spring 20, coiled about a spring-retaining pin 21, fixed in the plate 18 and depending therefrom and entering loosely a socket therefor in the base A. The pin 21 at its lower end is provided with a head 22, 25 located in a lower and enlarged portion of the pin-receiving socket, the head 22 being adapted to contact against a shoulder at the upper end of the enlarged socket, thereby preventing the uplifting of the plate 18 by the spring 30 20 beyond the desired limit of its travel. The plate 17 is secured to the arm 18 detachably conveniently by means of screws 23. The exposed under surface of this plate 17 may 35 be engraved or finished as a die in ornamental form, as illustrated in Fig. 4, thereby adapting it to emboss or finish the outer surface of the box-loop by compression with such ornamentation as desired.

- For receiving and holding the completed 40 box-loop as made by the workman who puts the parts together, but without having received its form or ornamentation in such manner as to form and finish the loop in this machine, an elongated finger, which I call a 45 "loop-stick" 24, is provided, which loop-stick is of such size in cross-section as adapts it to enter and properly form the made but unformed and to that extent uncompleted box-loop, which loop-stick is beveled and some- 50 55 what narrowed to a thin and narrowed edge at its front end and is provided with a shoulder 25 on one surface thereof, which serves as a stop against which the end of the loop will contact when placed on the stick. The loop- 60 stick 24 may be supported in position with reference to the jaws and with reference to the plates 15 and 17, but movable vertically in the manner illustrated in Figs. 1, 2, and 3 by providing an auxiliary base-piece 26, se- 65 cured to the base A conveniently by screws 27 28, in which base-piece two posts 28 are fixed, on and about which posts the stick 24 is movable vertically, being guided thereby. A sleeve 29 is advisably employed, which is 70 75 fixed in the loop-stick 24 and which fits

loosely around one of the guide-posts 28 and telescopes thereon. A spring 30, coiled about the sleeve 29 and about the post 28, rests at its lower end on the auxiliary base-piece 26 and bears yieldingly upwardly 70 against the loop-stick 24, being adapted to support the loop-stick yieldingly, as shown in Figs. 1 and 2. An enlarged head 31, secured to the top end of the guide-post 28 by a screw 32, serves as a stop against which the 75 loop-stick contacts and is prevented from escaping upwardly from the guide-post.

In use a box-loop B as made by a workman, but unfinished as to form and ornamentation, is pushed onto the loop-stick 24, as 80 illustrated in Fig. 2, and thereupon by any suitable means, which may be a screw or press or cam, the plate-arm 18 is forced down, carrying the embossing-plate 17 against the top of the box-loop, which going farther 85 down with the plate-arm is brought between the face-pieces 12 of the jaws 4 and down onto the loop-plate 15, and being forced farther down the jaws are caused to close toward each other, bringing the face-plates 12 90 against the sides of the loop and pressing the embossing-plate 17 against the top surface of the loop against the resistance of the under plate 15 to such extent as to impress or emboss the top or outer surface of the box-loop 95 with the design of the plate or die 17, the result being the forming by compression of the box-loop in the approximately square and finished form desired, which completion in this respect being under great pressure so 100 forms and sets the leather of the box-loop that it retains its form and ornamental finish thereafter.

In the modified form of construction shown in Figs. 6 and 7 the loop-stick 24 instead of being mounted on upright posts, like those shown in Figs. 1, 2, and 3, which are fixed on an auxiliary base 26, is supported dependingly from the plate-arm 18. This may be accomplished by providing the 105 loop-stick 24 with upright legs 33, which enter and travel vertically in sleeves 34, fixed in an extension 35 of the arm 18, which extension may be made as an addition and secured thereto by means of screws 36. An 110 enlarged head 37 on the top of one of the legs 33 fits in an enlarged portion of the socket therefor in the extension 35 and resting on a shoulder therein prevents the descent of the loop-stick 24 beyond the required distance 115 120 from the plate 17. In this form of machine the loop-stick 24, subject to its movement vertically on the arm 18, moves therewith vertically into and out of position between the forming-jaws.

What I claim as my invention is—

1. A box-loop machine, comprising a base, a pair of angled jaws pivoted on the base and provided with loop-forming faces, means for holding the jaws open yieldingly, a bottom- 130

loop-forming plate between the jaws resting on arms of the jaws, an opposite outer-surface loop-forming plate movable toward and from the bottom plate, and an interposed 5 loop-stick movable toward and from the bottom-loop-forming plate.

2. In a box-loop machine, a base having a jaw-receiving recess in its surface, angled side-loop-forming jaws in said recess pivoted 10 opposite each other to standards of the base at the ends of the recess, a bottom-loop-forming plate between the jaws and resting and supported constantly on inturned arms thereof, an opposite top-loop-forming plate movable 15 toward and from the bottom plate, and means for holding a loop in the space between and adjustable to the loop-forming devices.

3. In a box-loop machine, a base having a recess in its surface the recess being provided 20 with a jaw-supporting floor, angled opposite jaws pivoted at their sides in the recess, means in said floor bearing against and adapted to lift the laterally-disposed arms of the jaws 25 yieldingly, a bottom-loop-forming plate supported on the laterally-adjacent projecting arms of the jaws, and an opposite top-loop-forming plate adapted to be moved toward and from the bottom-loop-forming plate.

30 4. In a box-loop machine, a movable loop-stick, tilting jaws having side-loop-forming face-plates opposite each other, mounted directly on and movable laterally in both directions by and with the jaws, a bottom-loop-forming plate between and supported constantly on the jaws, and an opposite top-loop-forming plate adapted to move toward and from the bottom plate and by its movement against a loop on the stick interposed 35 between the top and bottom plates, to compel such movement of the jaws toward each other as thereby to press the four sides of an interposed loop.

5. In a box-loop machine, a base having a 45 jaw-supporting floor, jaws pivoted on the base adapted to rest on the floor when closed against an interposed loop, means in the base adapted yieldingly to lift the inturned adjacent arms of the jaws away from the floor, 50 movable means adapted to press against the outer surface of a loop interposed between the jaws and thereby to communicate pressure against and movement to the arms of the jaws bringing the jaws to their seats on the floor and against the sides of the interposed loop.

6. In a box-loop machine, a base, angled 60 jaws pivoted on the base to be seated on the base when put in operation, opposing face-plates on and movable laterally by and with the jaws, and means in the base pushing yieldingly against adjacent inturned arms of the jaws for holding the jaws yieldingly open and away from their seats on the base.

7. In a box-loop machine, a base, angled 65 jaws pivoted on the base and having laterally inwardly projecting and abutting arms, a bottom plate between the jaws resting on the laterally-projecting arms, and pins on the plate entering recesses therefor in the 70 ends of the laterally-projecting and complementary arms and holding the plate releasably in position on the arms of the jaws.

8. In a box-loop machine, a base, angled 75 tilting jaws pivoted on the base, laterally-projecting arms on the jaws, an overhanging loop-plate-carrying arm movable toward and from the laterally-projecting arms of the jaws, legs on the overhanging arm slidale in ways therefor in the base, and a spring adapted to 80 hold the overhanging arm yieldingly at a distance from the base and the jaws.

9. In a box-loop machine, a base, jaws pivoted thereon and adapted to press against and form the sides of a box-loop, a plate-arm carrying a loop-forming plate, legs projecting from the arm and movable in the base permitting the movement of said loop-forming plate into and from the space between said jaws, a spring holding the plate yieldingly away from the base and the jaws, and means on the jaws to receive the pressure and to cause the jaws to be moved toward each other by the movement of said loop-forming plate on said plate-arm toward said 95 jaws and through an interposed box-loop.

10. In a box-loop machine, a base, jaws pivoted thereon and adapted to press against and form the sides of a box-loop, a plate-arm carrying a loop-forming plate, legs projecting 100 from the plate and movable in the base permitting the movement of said loop-forming plate into and from the space between said jaws, a spring holding the plate yieldingly away from the base and the jaws, and a loop-stick interposed and supported movably in 105 the space between the loop-forming plate and said jaws.

11. In a box-loop machine having movably-approaching box-loop side-forming jaws 110 and approaching top and bottom box-loop-forming members, a loop-stick supported movably in the space between these box-loop-forming devices.

12. In a box-loop machine, the combination 115 with box-loop side-forming jaws, a box-loop-forming bottom plate, and a movable plate-arm carrying a complementary box-loop top-forming plate, of a loop-stick suspended on and movable toward and from said plate-arm in and across the space between 120 said box-loop-forming members.

In testimony whereof I affix my signature in presence of two witnesses.

HORATIO S. KEMP.
